UNITED STATES PATENT OFFICE.

JOSEPH KNISTROM, OF ATTLEBORO, MASSACHUSETTS, ASSIGNOR OF ONE-HALF TO EMIL L. JOHNSON AND ONE-HALF TO OLOF LUNDSTEN, BOTH OF ATTLEBORO, MASSACHUSETTS.

BELT BUCKLE.

Application filed July 22, 1925. Serial No. 45,246.

- This invention relates to an improved construction of belt buckle for retaining a belt in adjusted position about the body of the wearer; and the object of this invention 5 is to provide such a buckle with a body portion having side flanges between which one end of the belt is received and having a bail member pivotally mounted between the flanges with a gripper member carried by 10 the bail member and movable relatively thereto for the purpose of independent adjustment for gripping and binding the belt against the inner surface of the body portion of the buckle.
- 15 A further object of the invention is to form the gripper member in a roller gripper cam shape to roll relatively to the movement of the bail member and cause the cam portion to bind the belt against the buckle body.
- 20 The invention further consists in providing cooperating means between the bail member and the cam member carried thereby for limiting the relative movement of the gripper, which limiting means serves to 25 cause a movement to and from the belt gripping position by a similar movement of the bail.

With these and other objects in view, the invention consists of certain novel features 30 of construction, as will be more fully described, and particularly pointed out in the appended claims.

In the accompanying drawing:

- Figure 1 is a view of the under side of 35 my improved belt buckle showing the bail member as pivotally mounted between the rearwardly-turned side walls thereof and the gripper member carried by the bail.

- Figure 2 is a perspective view of the bail 40 member removed and showing the slot therein adapted to receive the gripper member.

Figure 3 is a perspective view of the gripper member as struck from sheet stock having a bail engaging tongue portion.

- Figure 4 shows the gripper member as 45 partially rolled into tubular form in which the enlarged portion of the engaging face of the gripper serves to provide a gripping cam action on the belt.

- Figure 5 is a perspective view showing the gripper mounted in the bail.

Figure 6 is a sectional side elevation showing a portion of one end of the belt as con-

nected to the bail and the other end of the belt as bound in the buckle body by the 55 gripper.

Figure 7 is an enlarged sectional view on line 7—7 of Figure 6 through the bail and gripper.

Figure 8 is an enlarged fragmental view 60 showing the cam-shaped gripper as binding a portion of the belt against the inner face of the buckle.

It is found in the practical operation of belt buckles of this character, of advantage 65 to pivotally mount a bail member between the flanges of the buckle body and to mount in the bail member a roller gripper member having a cam action, whereby the cam is permitted a certain amount of movement 70 relatively to that of the bail to permit the cam by revolving, to grip and securely bind the belt against the inner surface of the buckle body; also to provide simple and effective means in the bail and gripper for 75 limiting the rotating motion of the cam gripper so that when a sufficient biting grip is exerted by the gripper on the belt, it is prevented from further rotation, to secure the belt in the buckle; and the following is 80 a detailed description of the present embodiment of my invention and showing one means by which these advantageous results may be accomplished:

With reference to the drawings, 10 designates the front plate of the belt buckle, which is provided with rearwardly-extending side flanges 11 having inturned edges 12 under which the free end of the belt is received to be gripped in the body, the buckle being also provided with rearwardly-extending side ears 13 on said flanges in which the bail member 14 is mounted to swing on its pivots 15.

The outer portion of this bail member is 95 provided with an opening 16 through which the end portion 17 of the belt is passed and fastened by any suitable means. That portion of the bail between the pivots 15 being preferably turned inwardly at substantially 100 right angles as at 18 and provided with a slot 19 intermediate its edges.

In order to provide a suitable roller cam shaped gripping member for this bail, I have struck from sheet stock a plate 20 which has 105 a tongue portion 21 on one edge and a thick-

ened portion 22 on its working face whereby when this sheet member is rolled up into the form best illustrated in Figure 4, it forms a tongue portion 21 which is narrower than the full width of the gripping surface and is passed through the slot 19 of the bail to abut against the end 25 of the gripping roller, thereby providing stop shoulders 23 and 24 on the ends which are spaced one from the other a sufficient distance to permit a relative rotation between the bail and the gripper and serving as stops to limit this relative rotating movement, whereby a swinging movement of the bail back from operating position serves to lift the gripper from engagement with the belt, to release the belt to be readily removed from the buckle, and also the swinging of the bail back into operating position serves to carry this gripper into engagement with the surface of the belt so that tension on the belt will cause the tubular gripper to rotate in its bail whereby the cam serves to bind the belt end 27 against the inner surface of the buckle body.

In some instances, I roughen or corrugate the cam surface 26 so as to better grip the belt and prevent it from slipping.

My improved belt buckle is very simple and practical in construction and is effective in its operation, and by its use a belt may be firmly retained and bound in any desired position in the buckle body about the body of the roller and firmly held in any adjusted position; also by my improved construction belts of widely varying thicknesses may be gripped and held by my improved construction of gripper.

The foregoing description is directed solely towards the construction illustrated, but I desire it to be understood that I reserve the privilege of resorting to all the mechanical changes to which the device is suscepti-

ble, the invention being defined and limited only by the terms of the appended claims.

I claim:

1. A buckle comprising a body portion having a front plate with side belt guiding flanges, a bail member to which the end of the belt may be secured pivotally mounted between said flanges, said bail having a portion between the pivotal mounting extending at right angles to the plane of the bail, said portion having a slot formed therein and a sheet metal gripper member folded into tubular cam shape with its ends disposed at each side of said right angularly extending portion and a tongue on said gripper loosely looped through said slot to permit a relative motion of said bail and gripper for the latter to bind the belt against the body, the ends of said gripper member on each side of the slotted portion acting to limit the relative movement of the bail and gripper members.

2. A buckle comprising a body portion having a front plate with side belt guiding flanges, a bail member to which the end of the belt may be secured pivotally mounted between said flanges, said bail having a portion between the pivotal mounting extending at right angles to the plane of the bail, said portion having a slot formed therein and a sheet metal gripper member folded into tubular shape with a thickened portion providing a cam surface and a tongue on said gripper loosely looped through said slot to permit a relative motion of said bail and gripper for the latter to bind the belt against the body, the ends of said gripper member on each side of the slotted portion acting to limit the relative movement of the bail and gripper members.

In testimony whereof I affix my signature.
JOSEPH KNISTROM.
